ABSTRACT

An electric high-voltage apparatus such as an electron accelerator or the like includes a tank having a wall and a tank access located in the wall for making the interior of the tank accessible. An electrical discharge vessel is disposed in the tank and contains replaceable parts. The vessel has a wall and is insulatingly spaced from the tank wall. A vessel access is located in the vessel wall for making the replaceable parts accessible. A tube-like air lock device having a longitudinal axis is movable in the tank transversely to this axis from a given rest position to an operative position located between the tank access and said vessel access. The device includes expansion structure for defining a gas-tight passage between the vessel access and the tank access when the device is in the operative position thereof.

**ELECTRICAL HIGH VOLTAGE APPARATUS
EQUIPPED WITH A MOVABLE AIR LOCK DEVICE
FOR EXCHANGING THE FILAMENT OF AN
ELECTRON GUN**

The invention relates to an electrical high-voltage apparatus with an electrical discharge vessel disposed in a tank or vessel. The apparatus is insulated with respect to the vessel by a vacuum or a protective gas. The apparatus is equipped with a movable tubular air lock which makes it possible to establish a passage between respective closable openings in the tank wall and the vessel wall. The passage is sealed against these walls and the vacuum or the protective gas filling. The passage affords access to components of the discharge vessel for replacing the same.

The invention is especially adaptable for an electron accelerator which can for instance serve as the beam source for an electron microscope. Here, the requirement exists to pass through the walls of the discharge vessel and the tank and remove and replace the cathode which is located in the discharge vessel. So that the gas filling or the vacuum can be maintained in the tank during this replacement procedure, a tubular air lock is used which is moved between the openings of the discharge vessel and the tank.

Such an arrangement is known, for instance, from the German published Patent application No. 1,205,208. Here the tubular air lock is moved in the direction of its axis. In the rest position, the air lock is located outside of the tank on upper side of the latter. The space required for the arrangement is therefore increased in the vertical direction. Furthermore, the sealing of the tubular air lock is made more difficult by the requirement that the air lock must be movably slidable in its guide structure.

Accordingly, it is an object of the invention to provide an electrical high voltage apparatus equipped with a movable air lock device which overcomes the disadvantages of the above-referred to prior art apparatus.

It is also an object of the invention to provide an electrical high voltage apparatus equipped with a movable air lock device which is of compact configuration and affords a reliable gas-tight access to parts contained in the apparatus.

According to a feature of the invention, a tubular air lock is situated within the tank of a high voltage apparatus of the type mentioned above. The air lock remains within the tank during the operation of the discharge vessel. The air lock device has a longitudinal axis and is movable into the transfer or operative position in a direction transversely to this axis. The air lock device includes expansion means for defining a gas-tight passage between an access means located in the wall of the tank and an access means in the wall of the vessel when the air lock device is in the operative position. The gas-tight seal is formed with the sealing surfaces of the vessel and the tank sealing flanges of the expansion means. The invention affords the advantage that no additional structural height is required for the tubular air lock since it is always located in the tank. In addition, the sealing of the tubular air lock against the walls of the tank and the discharge vessel is substantially simplified because the sealing means are merely pressed against each other and are therefore not stressed with sliding friction and shear.

The tubular air lock device can include an expandable member in the form of a metal bellows. However, the expandable member can also be configured in the form of tubular members telescopically joined one within the other. The expansion means of the air lock device can include linkage means having a knee lever which in the operative position extends beyond dead center position. The knee lever comprises elongated members which are pivotally joined at a pivot connection to form an acute angle. Each of the elongated members has an end pivotally connected to the expandable member, and means are provided for moving the linkage members angularly with respect to each other at the operative position so that the pivot connection moves laterally through the dead center position of knee lever to cause the acute angle to become an obtuse angle. The knee lever can act upon threaded rings which are attached at the sealing flanges and which are adjustable. The threaded rings make it possible to adapt the spacing of the sealing flanges to the spacing between the respective sealing surfaces of the tank and the vessel.

The linkage means of the tubular air lock device advantageously includes a set of rails upon which a carriage moves for carrying the expandable member. A drive means is operatively connected to the carriage for moving it and the expandable member laterally to the operative position. The carriage includes means operatively connected to the drive means and to the knee lever for extending the expandable member at the operative position in response to a further actuation of the drive means. In this way, it is possible to move the tubular air lock into the operative position as well as to expand it with a single driving operation. The same applies for the reverse procedure, namely, removing the tubular air lock device from the operative position and returning it to its rest position. In this connection, it is furthermore advantageous to provide resilient means in the form of springs which act in the sense of folding the knee lever; this makes it easier for expandable member of the tubular air lock device to become shorter, for instance, because of its own longitudinal elasticity. The same or correspondingly acting separate springs can, however, also act upon the sealing flanges in the sense of shortening the expandable member and thereby draw the sealing flanges away from the sealing surfaces of the tank and the discharge vessel when the tubular air lock is moved away from the operative position. A detent can be provided which holds the tubular air lock in the operative position at the start of its return until the sealing flanges have separated safely from the sealing surfaces.

During the operation of the vessel, the tubular air lock may be situated in any given part of the tank at which it disturbs the field distribution between the tank and the discharge vessel as little as possible. Preferably there is provided in the tank a lateral pocket or enclosure which receives the tubular air lock during the operation of the vessel. This pocket is closed off advantageously by a metal plate when the tubular air lock is moved into the pocket, so that the inner wall of the tank has no projecting parts which would cause discharges.

Each time the air lock is moved to the operative position and used, a loss of protective gas occurs which cor-

responds to the free volume of the tubular air lock. This loss can be largely reduced by inserting a removably insertable filler body into the tubular lock which substantially fills the volume of the tubular lock.

Although the invention is illustrated and described herein as electrical high voltage apparatus equipped with a movable air lock device, it is nevertheless not intended to be limited to the details shown, since various modifications may be made therein within the scope and the range of the claims. The invention, however, together with additional objects and advantages will be best understood from the following description and in connection with the accompanying drawings in which:

FIG. 1 is an elevation view, in section, of an electron accelerator equipped with a tubular air lock shown in the rest position;

FIG. 2 an elevation view of the electron accelerator of FIG. 1 showing the tubular air lock in the transfer position;

FIG. 3 is a plan view of the tubular air lock and its guidance members with the cover of the vessel removed; and,

FIG. 4 is a side view of the tubular air lock guidance members taken along line IV—IV of FIG. 3; and,

FIG. 5 is another embodiment of the air lock.

In FIGS. 1 and 2, the wall of the discharge vessel is designated with reference numeral 1. The wall 1 consists of insulating material such as ceramic. The discharge vessel is closed off in a vacuum-tight manner by means of a metal lid 2 which carries the cathode 3. Above the cathode, vessel access means comprising an opening in the lid 2 and a threaded insert 4 that closes off the opening vacuum tight is provided.

The discharge vessel is located in a metal tank 5 which is closed by a lid 6 in a pressure-tight manner. The lid 6 of the tank has tank access means comprising an opening above the cathode 3 and an insert 7 which closes the opening vacuum-tight. The space 8 between the discharge vessel 1, 2 and the tank 5, 6 is filled with an electro-negative gas, for instance, sulfur hexafluoride, SF₆, at a pressure of 4 atmospheres. During operation of the discharge vessel, the lid 2 with the cathode 3 is at high negative potential, for instance, several hundred kilovolts, while the tank 5, 6 is at ground potential.

In order to replace the cathode 3, the inserts 4 and 7 must be removed while maintaining the gas filling in the space 8 as far as possible.

For this purpose, an expandable tubular air lock member designated by reference numeral 9 is provided, which in the illustrated embodiment is configured as a metal bellows that can expand along its longitudinal direction. The tubular air lock 9 is provided at the upper and lower edge with sealing flanges 10 and 11, respectively. Seal rings 12 and 13 are inserted into flanges 10 and 11 respectively, and are pressed against the sealing surfaces 14 and 15 of the tank lid 6 and the lid 2 of the discharge vessel in the transfer or operating position as shown in FIG. 2. At each sealing flange is attached a threaded ring 16 and 17, respectively. Pressure rings 18 and 19 engage the threaded rings 16 and 17 which are pushed apart by two knee levers 20a and 20b when the tubular air lock is moved into the transfer position; this action is explained later in more detail. In this way, the sealing flanges 10 and 11 are pushed via

the threaded rings 16 and 17 against the lid 2 of the discharge vessel and the lid 6 of the tank, this being especially evident in FIG. 2. By turning the threaded rings 16 and 17, the spacing of the sealing flanges 10 and 11 can be matched to the spacing between the lid of the discharge vessel 2 and the tank lid 6 in such a manner that the sealing rings 12 and 13 are under a suitable pressure in the transfer position. Tension springs 21 and 22 are located between the pressure rings 18 and 19 which cause the knee levers 20a and 20b to fold and thereby initiate the shortening of the tubular air lock when it is moved away from the operating position.

As may be seen particularly from FIGS. 1, 3 and 4, the tubular air lock 9 is supported on a carriage 23, which is movable in a direction perpendicular to the axis of the tubular air lock. The knee levers 20a and 20b are linked to this carriage 23 and are connected by joints at their outer ends to the pressure rings 18 and 19. The carriage 23 runs on two guide rails 24 and 25 by means of support rails 26 and 27 of which one (27) is configured as a toothed rack member. For driving the carriage 23, a pinion 28 is provided which engages with the rack 27 and can be operated from the outside by a crank 29.

In the tubular air lock 9, there is located a removable filler 30 which largely fills the volume of the air lock.

The drive for moving the carriage 23 with the tubular air lock 9 operates as follows:

According to FIG. 1, the carriage 23 is in its rest position in an enclosure in the form of a lateral pocket 5a of the tank wall 5. The pocket 5a is here closed on the inside by a metal plate 31 which is connected with the carriage 23. If the crank 29 is now turned, the carriage 23 slides on the guide rails 24 and 25 to the left into the operating position. Upon reaching the operating position, the pressure rings 18 and 19 with projections 18a and 19a, respectively, meet the fixed counter surfaces 32, 33 of the tank lid 6 and the vessel lid 2 respectively. These stops prevent a further movement of the tubular air lock 9 perpendicular to its axis. Upon further rotation of the crank 29, the carriage 23 moves further to the left and, with the tubular air lock 9 held fixed, the knee levers 20a and 20b are now spread and the sealing flanges 10 and 11 are tensioned via the pressure rings 18 and 19 against the sealing surfaces 14, 15 of the tank lid 6 and the vessel lid 2 respectively. The knee levers 20a and 20b are here pushed beyond dead center so that they exert no return force on the transfer gear. Their end position is defined by a projection 23a of the carriage 23 which makes contact with the pressure ring 18; this position is shown in FIG. 2. The range of displacement of the carriage 23 between the arrest of the tubular air lock 9 in the transfer position and the impact of the carriage at the pressure ring 18 is noted by a slight increase of the torque at the crank 29. The end of the movement can clearly be felt by the hard stop.

Referring to FIG. 1, the center joints of the knee levers 20a and 20b are supported on the carriage 23 in such a way that there is clearance in the direction of the tubular air lock axis. In this way, lack of parallelism (perpendicular to the plane of the drawing of FIGS. 1 and 2) between the tank and vessel lids as well as between these lids and the carriage 23 is compensated

for. Furthermore, this manner of support ensures that the same pressure automatically adjusts itself at the upper and lower seal.

With this, the move of the tubular air lock into the transfer position is completed. Now the insert 7 can be removed from the tank lid 6 and the filler 30 can be removed from the tubular air lock 9. With this, and after destroying the vacuum in the discharge vessel, the insert 4 can be threadedly disengaged from the tank lid 2 so that the cathode 3 is accessible and can be exchanged by means of a suitable tool.

After closing the air lock in the reverse sequence, the tubular air lock is run back into its rest position by turning the crank 29 in the opposite direction. At the beginning of this movement, tubular air lock 9 is at first held in the operating position by the adhesion of the sealing rings 12 and 13 at the sealing surfaces 14 and 15. The carriage 23 moves away from the tubular air lock 9 to the right and pulls the knee arms 20a and 20b beyond dead center. The distance between the pressure rings 18 and 19 is shortened under the influence of the tension springs 21, 22. The tubular air lock 9 is also allowed to become shorter thereby under the influence of the longitudinal spring loading, and after leaving the self-locking range in the knee lever linkage, the pressure rings 18 and 19 make contact with the carriage 23. The sealing rings 12 and 13 have then separated from the respective sealing surfaces 14 and 15. The parts can also be so disposed that the tension springs 21, 22, in addition to acting on the pressure rings 18 and 19, also act on the sealing flanges 10 and 11 in the sense of shortening the tubular air lock 9, for instance, by providing corresponding stops between the pressure rings 18 and 19 on the one hand, and the sealing flanges 10 and 11 on the other hand.

By further turning the crank 29 in the same sense, the carriage 23 with the tubular air lock 9 is then run into the pocket by 5a. The pocket 5a is closed by the plate 31 in such a manner that the inner surface of the tank 5 has an essentially smooth surface at this location.

FIG. 5 illustrates another embodiment of the expandable tubular air lock. It consists of two tubes 34 and 35 mutually telescoped which are sealed with respect to each other. The sealing flanges are again designated by reference numerals 10 and 11.

In the shown example of an embodiment according to FIGS. 1 to 4, the tubular air lock moves in a rectilinear direction. The invention is not limited to this form of motion; for instance, a rotating motion with circular-arc guidance can be provided. This motion of the tubular air lock is also perpendicular to its axis.

I claim:

1. Electric high-voltage apparatus such as an electron accelerator comprising a tank having a wall, tank access means located in said wall for making the interior of said tank accessible, an electrical discharge vessel disposed in said tank and containing replaceable parts, said vessel having a vessel wall and being insulatingly spaced from said tank wall, vessel access means located in said vessel wall for making the replaceable parts accessible, and a tube-like air lock device having a longitudinal axis, said device in assembled condition always being positioned entirely within said tank, and means for moving said device in said tank transversely

to said axis from a given rest position to an operative position located between said tank access means and said vessel access means, said device comprising expansion means for defining a gas-tight passage between 5 said vessel access means and said tank access means when said device is in said operative position thereof.

2. The apparatus of claim 1, said vessel wall being insulated from said tank wall by a protective gas.

3. The apparatus of claim 1, said vessel wall being insulated from said tank wall by a vacuum.

4. The apparatus of claim 1 comprising sealing surfaces formed on said walls respectively in surrounding relation to corresponding ones of said access means, and said expansion means comprising an expandable 15 member having sealing flanges at respective ends thereof, and linkage means connected to said expandable member for extending the latter to press said sealing flanges gas-tight against said sealing surfaces respectively.

20 5. The apparatus of claim 4, said expandable member being a tubular metal bellows.

6. The apparatus of claim 4, said expandable member being at least two tubular members telescopically connected with each other.

25 7. The apparatus of claim 4, said linkage means comprising a knee lever having elongated members pivotally joined with each other at a pivot connection to form an acute angle, each of said elongated members having an end pivotally connected to said expandable 30 member, and means for moving said linkage members angularly with respect to each other at said operative position so that the pivot connection moves laterally to cause said acute angle to become an obtuse angle.

8. The apparatus of claim 7, said expandable 35 member having rings threadably engaging respective ones of said sealing flanges for adjusting the positions of the latter, said elongated members being in operative connection with said rings.

9. The apparatus of claim 7, said linkage means comprising a set of rails, and a carriage mounted on said rails for carrying said expandable member, and a drive means connected to said carriage for moving said carriage and said expandable member laterally from said rest position to said operative position, said carriage including means operatively connected to said drive means and to said knee lever for extending said expandable member at said operative position in response to a further actuation of said drive means.

10. The apparatus of claim 7, said device comprising 50 resilient means connected to opposite end portions of said expandable member and acting in a direction to fold said knee lever.

11. The apparatus of claim 10, said resilient means being springs.

12. The apparatus of claim 1, said tank being formed with a lateral enclosure for accommodating said air lock device in said rest position.

13. The apparatus of claim 9, said tank being formed with a lateral enclosure for accommodating said air lock device in said rest position, said carriage having a metal plate for closing said enclosure when said air lock device is in said rest position.

14. The apparatus of claim 4, comprising a filler piece removably insertable into said expandable 65 member.
